LOCK

Filed Jan. 26, 1928

UNITED STATES PATENT OFFICE

JOSEPH UNGER, OF BROOKLYN, NEW YORK

LOCK

Application filed January 26, 1928. Serial No. 249,741.

My invention relates to locks and refers particularly to locks adapted to operate in connection with door latches.

One of the objects of my device is a locking means operative with a door latch in which the pressure incident to an attempt to force the latch when the locking means is in locked position will not bear upon the locking tongue but will be exerted against an immovable butment, thus causing the forcing of the latch into open, or movable, condition practically impossible.

Numerous other valuable attributes of the lock of my invention will be evident upon a consideration of my specification and its accompanying drawings.

In the accompanying drawings illustrating one form of the device of my invention, similar parts are designated by similar numerals.

Figure 1 is an interior view of one form of the lock of my invention, with the top, or cover, removed, the lock being in locked position.

Figure 2 is a broken view similar to Figure 1 with the lock in unlocked position.

Figure 3 is a section through the line 3—3 of Figure 1 with the cover on the device.

Figure 4 is a section through the line 4—4 of Figure 1 with the cover on the device.

Figure 5 is a perspective view of the several elements comprising the parts movable by the door handle.

Figure 6 is a perspective view of the lock catch.

The particular form of the device of my invention illustrated in the accompanying drawings comprises a casing having the bottom 10, the front 11, the back 12 and the ends 13 and 14.

A top, or cover, 15 is fixedly attached by screws passing therethrough and threaded within the opening 16 of the member 17, the opening 18 of the back extension 19, and the opening 20 of the butment 21. The member 17 is fixedly attached to the bottom 10, the end 14 and the front 11. The member 19 is fixedly attached to the bottom 10. The butment 21 is fixedly attached to the bottom 10, the end 13 and the front 11. The threaded

bolt 22 threaded within the member 23 of the bottom 10 allows of attachment of an ordinary tumbler cylinder (not shown). The bottom 10 has an annular opening 24.

The rod 25 carries the latch 26, capable of movement through the opening 27 of the front 11, and the plate 28. The rod 25 passes through an opening in the fixed upright 29 and the spring 30 tends to keep the latch 26 in extended position and the plate 28 and the upright 29 in abutment.

A locking member 33 having a hollow annular bearing 31, the interior of which is of angular formation passes through the opening 32 of the bottom 10 and is revoluble 65 therein.

The locking member 33 has an inclined recess 34, the locking abutting member 31 and the latch moving member 36.

The locking member 33 also carries the 70 extended annular sleeve 62.

A spring support 37 is fixedly attached to the bottom 10, and the upper angular end of the support 37 passes through the angular opening 37' in the cover 15. A spring 38 75 carried by the support 37 and abutting upon the locking member 33 tends to maintain the member 33 in abutment with the butment 39 which is fixedly attached to the bottom 10, the end 13 and the back 12.

The butments 17, 21 and 39 and the member 19 may be integral parts of the bottom 10 or of the sides and front of the casing if desired.

Positioned upon the locking member 33 is 85 a member 40, the opening 41 of which is slightly larger than the sleeve 62 which passes through it. The member 40 carries a spring 42 abutting upon the upright 29 and tending to keep the outer edge of the member 40 extended beyond the outer edge of the locking members 33 and 43 the opening 41, however, allowing the faces of these two members to be flush with each other under tension. The object of the member 40 is to cause the locking tongue to snap into locked and unlocked 95 position as will be evident upon a consideration of my device.

Positioned upon the member 40 is a removable locking member similar in shape to the 100

bearing locking member. It comprises the body 43, having the inclined recess 44, the lock abutting member 45 and the latch moving member 46. The removable locking member 43 carries the exteriorly annular boss 47 which is interiorly of angular formation and which extends through the opening 48 of the top 15.

10 The lock operating means comprises two annular members 49 and 50 movable through the openings within the front 11. The interior portions of these two members 49 and 50 are pivotally connected by the yoke 51 having the extended locking tongue 52 and carried revolvably by the screw 53 threaded into the bottom 10.

15 Slidable along the outer face of the two locking members 33 and 43 is a lock catch which comprises the body 54 having the extended locking arms 55 and 56 and the recess 57.

20 The means for operating the lock comprises two angular bars 58 and 59, the bar 58 having an extended threaded end 60, threaded into an opening within the bar 59, the two bars 58 and 59 being spaced, so that either can be turned without imparting movement to the other. The bar 58 extends into the opening of the boss 47 and the bar 59 extends into the opening of the boss 31. Each bar has a handle, or knob, (not shown) as its extended end.

25 The operation of the device is as follows:—

30 When the device is in the position shown in Figure 1, with the lock operating member 49 pushed inwardly, the lock catch is in such a position that the locking arm 56 abuts upon the butment 21 and the lock abutment member 45 and it is evident that the bar 59, which carries the outward knob cannot be revolved and hence cannot be used as a means for moving the latch 26. The locking member 33, however, can be moved as its latch moving member 36 is capable of movement within the recess 61 of the lock catch and hence the bar 58 carrying the inward knob can be revolved, operating the latch 26.

35 It is evident that simply reversing the lock catch 55—56 and bringing the members 54, 55 upwardly will reverse the lock operating mechanism, and allow bar 59 to operate the lock and prevent bar 58 from operating it.

40 It is to be further noted that the latch may be readily reversed by drawing it inwardly releasing it from the front 11 and replacing it in reverse position.

45 If the latch operating member 50 be pushed inwardly, the locking tongue will move the mechanism into the position shown in Figure 2. The slidable lock catch 54 has now moved so that the locking arm 56 has moved from abutment 21 and 45, and the latch may be operated by the revolution of either bar 58 or 59.

50 It will be further noted that by simply re-

moving the lock catch 55—56 the lock is converted into an ordinary non-lockable latch device.

55 It is to be particularly noted that all pressure incident to endeavoring to move the latch when it is in locked position is brought by one of the members 35 or 45 and the member 56 against the fixed butment 21 thus causing an absolute impossibility of producing an unlocked condition, and no pressure, or stress, is brought to bear upon the locking tongue 52, as is incident in locks generally, thus preventing the breaking or bending of this tongue.

60 I do not limit myself to the particular size, shape, number or arrangement of parts as shown and described as these are given simply as a means for clearly describing my invention.

65 What I claim is:—

1. In a lock; in combination; a casing, a latch slidably movable through said casing and having an inwardly extended rod; a latch plate attached to the end of said rod; spring means for normally retaining said latch in outwardly extended position; a plurality of revolvable superimposed locking members, each having a recess and an extended member capable of abutment upon said latch plate; a fixed butment having a face parallel to a face of each locking member; a lock catch slidable between said butment and said locking means and abutable upon said butment between said butment and said locking members and slidable to a position to be received within a recess of one of said locking members to permit the latter to be revolved, said revolvable movement causing a latch movement, and when said lock catch is moved out of said recess to a position between said one locking member and butment, said locking member is not revolvable.

100 2. In a lock, in combination; a casing; a latch slidably movable through said casing and having an inwardly extended rod; a latch plate attached to the end of said rod; spring means for normally retaining said latch in outwardly extended position; a plurality of revolvable superimposed locking members, each having a recess and an extended member capable of abutment upon said latch plate; a fixed butment having a face parallel to a face of each locking member; a removable reversible lock catch slidable between said butment and said locking members and abutable upon said butment between said butment and said locking members and slidable to a position to be received by the recess of one said locking member and non-receivable by the recess of the other said locking member permitting the first mentioned locking member to be revolved and preventing the last mentioned locking member from revolution, and when in reversed position said lock catch preventing the revo-

lution of said revoluble locking member and permitting the revolution of said non-revoluble locking member.

3. In a lock, in combination, a casing; a latch slidably movable through said casing and having an inwardly extended rod; a latch plate attached to the end of said rod; spring means for normally retaining said latch in outwardly extended position; a plurality of revoluble superimposed locking members, each having a recess and an extended member capable of abutment upon said latch plate; a fixed butment having a face parallel to a face of each locking member; said lock catch being slidable between said butment and said locking members and abutable upon said butment and between said butment and said locking members and slidable to a position to be received within a recess of one of said locking members 70 to permit the latter to be revolved, said revoluble movement causing a latch movement, and when said lock catch is moved out of said recess to a position between said one locking member and butment, said locking member is not revoluble, said lock catch having a tongue receiving recess with inclined faces and an externally operative pivotal tongue positioned within said tongue receiving recess, the movement of which will slide 75 the lock catch. 80

20 4. In a lock, in combination; a casing; a

latch slidably movable through said casing and having an inwardly extended rod; a latch plate attached to the end of said rod; spring means for normally retaining said latch in outwardly extended position; a plurality of revoluble superimposed locking members, each having a recess and an extended member capable of abutment upon said latch plate; a fixed butment having a face 85 parallel to a face of each locking member; a movable reversible lock catch slidable between said butment and said locking members and abutable upon said butment between said butment and said locking members and slidable to a position to be received by the recess of one said locking member and non-receivable by the recess of the other said locking member, permitting the first mentioned locking member to be revolved and preventing the last mentioned locking member from revolution, and when in reversed position said lock catch preventing the revolution of said revoluble locking member and permitting the revolution of said non-revoluble locking 90 member, and an externally operative pivotal tongue means capable of sliding the lock catch into receptive and non-receptive positions for the locking member recesses. 95

5. In a lock, in combination; a casing; a latch slidably movable through said casing and having an inwardly extended rod; a latch plate attached to the end of said rod; spring means for normally retaining said latch in outwardly extended position; a plurality of revoluble superimposed locking 100

members, each having a recess and an extended member capable of abutment upon said latch plate; a lock catch; a fixed butment having a face parallel to a face of each locking member; said lock catch being slidable between said butment and said locking members and abutable upon said butment and between said butment and said locking members and slidable to a position to be received within a recess of one of said locking members 105 to permit the latter to be revolved, said revoluble movement causing a latch movement, and when said lock catch is moved out of said recess to a position between said one locking member and butment, said locking member is not revoluble, said lock catch having a tongue receiving recess with inclined faces and an externally operative pivotal tongue positioned within said tongue receiving recess, the movement of which will slide 110 the lock catch. 115
